UNITED STATES PATENT OFFICE

MITCHEL E. HADAD, OF BROOKLYN, NEW YORK

NEGLIGÉE PYJAMA GARMENT

Application filed March 12, 1931. Serial No. 522,069.

This invention relates to a negligée pyjama garment which comprises a construction combining the trousers portion of a pyjama suit with a negligée blouse. The entire construction producing the effect of a negligée garment having a pyjama trousers effect at the lower portion thereof. The invention further relates to the provision of an adjustable garment which may be readily adjusted to fit the human figure under widely varying conditions as to waist and hip measurements.

One feature of the invention relates particularly to the provision of an inside draw or adjustable belt suitably arranged at the top of the trousers portion of the garment whereby the same may be adjustably drawn into contact with the body of the wearer and is readily adjustable to different waist measurements of individual wearers.

Another feature relates to the provision of a flap or front cover portion attached to the leg portion of the trousers at the lower portion thereof and attached to the opposite leg portion from the crotch upwardly along the open front of the pyjama trousers and so constructed that it may be folded across the body of the wearer and attached at or near the waist or belt line serving thereby to close the front opening in the trousers and in its bottom portion to overlie the bottom portion of one trouser leg and thereby give the appearance of being merely a portion of the pyjama trousers.

Another feature is to connect the flap referred to, or make it integral with the negligée blouse at its top portion whereby when the blouse is closed the flap covers the front opening in the trousers and produces together with the blouse the general effect of a complete negligée garment which however is in its lower portion split to form pyjama trousers. It is also an object of the invention to provide a garment which may be used, without the blouse portion, as a pair of pyjama trousers in which the flap portion covers the front opening of the trousers and is attached at the waist line and with which a jacket or other upper garment may be worn.

A particular feature of the invention is the provision of the adjustable belt construction combined with the flap whereby garments may be produced in quantity and readily fitted to persons of different sizes and conformations without any substantial change in the garment itself. When the garment is applied and the belt suitably adjusted as by tying or by other means the flap is folded across the body and suitably attached at the belt or waist line by means of snap fasteners, snap hooks, buttons or similar fastening devices. Such fastening devices on the body portion of the garment may be readily moved so that a garment may be adjusted to fit different sized persons by merely shifting the position of the button or other fastening device. The waist size of the garment is determined, within reasonable limits, by the adjustment of the belt which may be arranged inside the garment near the waist line or under certain circumstances might be externally applied and of course with the inside belt a separate outside belt could be used if found desirable.

Referring to the drawings which are hereby made a part hereof, and on which similar reference characters indicate similar parts:

Figure 3 is a view similar to Figure 1 showing the flap held up across the body with the blouse and upper portion of the garment held in open position and Figure 4 is a view showing the garment separately with the flap extending outwardly and also showing how the flap is attached to the upper and lower portions of the garment.

In the drawings the lower or trousers portion of the garment is indicated generally at 1 having lower leg portions 2 and a flap portion 3 and a negligée blouse 4 which is attached to the trousers as indicated at 5. As indicated at 6 there is a belt or cord inserted within a casing arranged on the inner side of the garment at a portion thereof generally representing the waist line of the garment. Such casing may be formed by stitching a strip of material around the 5 inner portion of the garment from the free edge of the open front on one side a distance substantially sufficient to extend around the body of a person of the largest size for which a particular garment is designed and not however extending over that 10 portion to which the flap is attached. By this construction the draw belt or cord or similar adjusting means may be employed to draw the garment into contact with the body 15 of the wearer at the waistline and such construction admits of considerable latitude of adjustment to persons of different sizes.

The blouse portion of the garment may be attached to the trousers portion by sewing 20 or may be integral therewith dependent upon the size and shape of the garment and upon the manner in which the same is to be cut from the material of which it is made.

The flap portion is attached to one side 25 of the front opening of the pyjama trousers from the bottom of the opening to the top of the trousers and extending upwardly merging into the side portion of the blouse. The flap is also attached to the trousers 30 from the lowest portion of the front opening to the crotch portion.

Below the crotch the edge of the flap is attached to the inner seam of the opposite pyjama leg portion to substantially the bottom 35 of the garment. This construction admits of the folding of the upper portion of the flap across the front of the body and attaching it to the belt or waist line portion thereof and the lower portion of the flap 40 will hang down in proper position over the corresponding trousers leg and give the general appearance of a complete pair of pyjama trousers. The upper portion of the flap also serves effectively to cover the front 45 opening in the pyjama trousers so that the necessity for providing fastening means along this portion of the garment is eliminated although such fastening means may be provided if found desirable. The outer 50 free edge of the flap is made continuous in its upward portion with the free edge of the blouse so that when the blouse is closed by folding its lower portions together the flap will be carried therewith and folded across 55 the front of the wearer.

The invention is not confined to a garment in which the blouse and trousers are combined into one piece. It will be apparent from the above description and from an inspection of the drawings that the blouse portion of the garment illustrated may be omitted and the flap attached as indicated above, to the trousers portion of a suit of pyjamas provided with a draw belt as indicated and 60 when the flap is folded across the front of the wearer it may be attached at or near the belt line to the opposed portion of the top of the trousers and will drop downwardly over the leg portion producing a pleasing appearance and also serving as a cover or 70 closure member for the upper open front portion of the pyjama trousers.

With a construction of the character just described, any preferred jacket or blouse may be worn as a separate garment. The 75 pyjamas however serve to produce the desired pleasing effect, and also being constructed in such a manner that they may be readily adjusted to fit different sized persons within reasonable limits, and the front portion effectively closed and protected by the flap.

Having thus fully described my said invention what I claim as new and desire to secure by Letters Patent, is:

1. In a combination garment, a pair of pyjama trousers having an open front, an open front negligée blouse attached to the upper portion of said trousers, one side of said blouse front having a portion extending downwardly to substantially the bottom of said trousers and having its confined edge attached to one side of the open front of the corresponding trousers leg and caught in the front seam of the trousers to the crotch, and attached at the inner seam of the opposite trousers leg from the crotch to the bottom portion of the trousers.

2. In a combination garment, a pair of pyjama trousers having an open front, an open front negligée blouse attached to the upper portion of said trousers, one side of said blouse front having a portion extending downwardly to substantially the bottom of said trousers and having its confined edge attached to one side of the open front of the corresponding trousers leg and caught in the front seam of the trousers to the crotch, and attached at the inner seam of the opposite trousers leg from the crotch to the bottom portion of the trousers and a draw belt inserted in the trousers at the upper portion thereof at the waist line.

In testimony whereof I affix my signature.
